UNITED STATES PATENT OFFICE

FREDERICK PURDY, OF FLINT, MICHIGAN, ASSIGNOR TO MARVEL CARBURETER COMPANY, OF FLINT, MICHIGAN, A CORPORATION OF ILLINOIS

THERMOSTATIC HEAT CONTROL

Application filed May 18, 1929. Serial No. 364,061.

This invention relates to a heating control for the intake systems of internal combustion engines and has special reference to an improved operating linkage for the heat control valve.

It is an object of this invention to provide an improved valve operating linkage incorporating a thermostatic control adapted to shift the phase of the heat control element relative to the controlling element, which in the illustrated embodiment comprises the throttle valve of a carburetor. It has heretofore been proposed to alter the heat supply to a carburetor or manifold jacket in such a way as to increase the heat supply for idling and to decrease or cut off the heat supply for in order to provide maximum power at full throttle as it is a well known fact that while heating a wet mixture increases the smoothness of operation it also reduces the weight of the charge entering an individual cylinder and thus reduces the power developed by a given cylinder volume. The present invention is directed towards shifting the phase relationship of the heat control mechanism in accordance with varying operating temperatures.

It is another object of this invention to provide an improved and simplified valve operating linkage embodying a thermostatic control that does not require complicated or special valve structures subjected to the fluids acted upon.

Other and further important objects of this invention will be apparent from the disclosures in the specification and the accompanying drawings.

This invention (in a preferred form) is illustrated in the drawings and hereinafter more fully described.

On the drawings:

Figure 1 is an elevation of an engine manifolding system illustrating the application of one form of the device of this invention.

Figure 2 is a fragmentary detail with parts broken away to show the valves.

Figure 3 is a fragmentary view similar to Figure 2, showing another embodiment of this invention.

Figure 4 is a fragmentary side view of the link of Figure 3.

On the drawings:

The manifold system of Figure 1 comprises a carburetor 10 having a throttle valve 11 on a shaft 12, the carburetor discharging into an intake manifold riser 13 jacketed as indicated by the reference numeral 14. The riser in turn opens into a horizontal distributing manifold 15 which is enveloped at the joint 60 by a continuation 16 of the riser jacket 14, this jacket 16 having twin ports 17 and 18 opening into an exhaust manifold 19 on either side of an exhaust cut off valve 20 carried by a cross shaft 21. A partition 22 extends downwardly in the jackets 14 and 16 to guide the exhaust gases from the port 17 down one side of the riser, around the bottom of the partition and up the other side of the riser, returning to the exhaust manifold through 70 the port 18.

The present invention relates to means for operating the valve 20, in the exhaust manifold, in proportion to the movement of the throttle valve 11. The throttle shaft 12 carries a lever 23 and the exhaust valve shaft 21 is provided with a lever 24. In Figures 1 and 2 the lever 24 is provided with a slot 25 at an angle thereto so located as to follow the arc of movement of a connecting link 26. When the exhaust valve is in its extreme open position this relationship obviously does not hold as the valve is rotated clockwise in Figure 2 toward its open position parallel to the axis of the exhaust manifold as it will be evident that in such a position if the link is swung to the inner end of the slot it will result in increasing the opening of the valve.

The thermostatic control for varying the responsiveness of the exhaust valve to movement of the throttle valve comprises a volatile liquid container 27 formed as an expandable corrugated cylinder one end of which is anchored by the fitting 28 and the other end is provided with a yoke 29 pinned to the link 26 at 30. As shown in Figure 2 in full lines the container 27 is partially expanded while the dotted lines indicate a collapsed position for a partial opening of the throttle

In this figure the exhaust valve 20 is provided with a wide cooperating seat 31 in the manifold which has the effect of permitting a valve movement of approximately 15° before opening of the main exhaust passage. This arrangement provides full exhaust gas diversion over a corresponding movement of the throttle valve and thus supplies more heat for operating conditions very closely approximating the slowest possible idling conditions.

The operation of the heat control, aside from the thermostatic features, may be briefly summarized as a proportional decrease in the diversion of exhaust gases through the riser jacket as the throttle is opened. The thermostatic control acts to increase the opening of the exhaust valve and thus decreases the diversion of exhaust gases as the temperature of the thermostatic element rises because a rise of temperature expands the container 27 and shifts the upper end of the link 26 towards the inner end of the slot 25 thus increasing the opening movement of the exhaust valve.

The modification of Figures 3 and 4 uses a plain lever 32 for the exhaust valve 20 and provides a two piece connecting link 33 and 34 separated by a cam 35 rotatable by a spiral bi-metal thermostatic strip 36 one end of which is anchored to the cam pivot 37 and the other end is pinned to the cam at 38 so that heating of the strip 36 causes uncurling thereof to rotate the cam counterclockwise, increasing the effective length of the link and thus shifting the exhaust valve towards its open position.

The two pieces of the link are held in alignment by a pilot 39 and are caused to follow the cam by a connecting spring 40.

In the operation of this form of the invention the phase relationship of the two valves is altered by a change in the effective length of the connecting link while in the first form of the invention the relationship is changed by changing the effective lever arm of the exhaust valve lever.

It will thus be seen that I have provided an improved and simplified thermostatic heat control for varying the heating effect in response to variations in operating temperatures.

I am aware that numerous details of construction may be varied through a wide range without departing from the principles of this invention, and I therefore do not purpose limiting the patent granted, otherwise than necessitated by the prior art.

I claim as my invention:

1. In a heat control for internal combustion engines the combination with valves arranged to throttle the exhaust gases and intake charge, means for connecting said valves, and thermostatically responsive means associated with said connecting means and adapted to vary the ratio of movement of the

exhaust controlling valve relative to the intake throttle valve.

2. In a heat control for internal combustion engines the combination with valves arranged to throttle the exhaust gases and intake charge, means for connecting said valves, and thermostatically responsive means adapted to vary the ratio of movement of the exhaust controlling valve relative to the intake throttle valve.

3. In combination with the exhaust and intake manifolds of an internal combustion engine, a control valve for said exhaust manifold, a bypass around said valve forming a heating jacket for said intake manifold, a throttle valve in said intake manifold, linkage connecting said control and throttle valves, and thermostatic means for varying the ratio of movement of the control valve relative to the throttle valve.

4. In combination with the exhaust and intake manifolds of an internal combustion engine, a control valve for said exhaust manifold, a bypass around said valve forming a heating jacket for said intake manifold, a throttle valve in said intake manifold, linkage connecting said control and throttle valves, and thermostatic means acting on said linkage for varying the ratio of movement of the control valve relative to the throttle valve.

5. In combination with a variable heat control linked to the speed control of an internal combustion engine, of thermostatic means for varying the ratio between said heat control and said speed control.

6. In combination with a variable heat control linked to the speed control of an internal combustion engine, of thermostatic means for varying the effective length of the linkage between said heat control and said speed control.

In testimony whereof I have hereunto subscribed my name.

FREDERICK PURDY.
